UNITED STATES PATENT OFFICE.

ANDREW W. NELSON, OF TERRE HAUTE, INDIANA, ASSIGNOR TO COLUMBIAN ENAM-
ELING & STAMPING CO., OF TERRE HAUTE, INDIANA, A CORPORATION OF IN-
DIANA.

HOLDING DEVICE.

Application filed November 13, 1923. Serial No. 674,492.

To all whom it may concern:

Be it known that I, ANDREW W. NELSON, citizen of the United States, residing at Terre Haute, in the county of Vigo and 5 State of Indiana, have invented certain new and useful Improvements in Holding Devices, of which the following is a specification.

My invention relates to a new and improved holding device.

One of the objects of my invention is to provide a new and improved holding device whereby a number of utensils or the like can be removably held in a suitable 15 carrier.

Another object of my invention is to provide a holding device whereby a number of cooking utensils, eating utensils and the like, are firmly, but releasably, held together in 20 a nested condition so that they can be easily stored and transported.

Another object of my invention is to provide a holding device of the character before specified, which shall be particularly 25 convenient for automobilists who desire to transport a large number of cooking and eating utensils in a relatively small space.

Another object of my invention is to provide a device of the character above specified in combination with a pail in which the said utensils may be carried.

Another object of my invention is to provide a device of the character before specified in combination with a pail having a 35 handle, so that the holding device can not be released while the said handle is in the vertical position, that is, while the nested utensils are being carried.

Other objects of my invention will be set 40 forth in the following description and drawings which show a preferred embodiment thereof.

Fig. 1 is a front elevation.

Fig. 2 is a top view of Fig. 1.

Fig. 3 is a central sectional view partially in elevation.

Fig. 4 is a plan view with the handle of the pail held in a horizontal position.

Fig. 5 is a top view of the holding rod or 50 member used as part of the holding device.

Fig. 6 is a detail side elevation, showing the right hand side of Fig. 1.

Fig. 7 is a sectional view on the line 7—7 of Fig. 2 and is partially in elevation.

Fig. 8 is a top view of the parts shown in 55 Fig. 6.

Fig. 9 is a top view of the parts shown in Fig. 7.

Fig. 10 illustrates the parts shown in Fig. 6 with the handle horizontal and the holding rod or member in the position in which it is about to be released from the handle. 60

Fig. 11 illustrates the parts shown in Fig. 7 when the device is in the position shown in Fig. 10. 65

Fig. 12 shows the parts illustrated in Fig. 10 just before the holding rod or member is finally released.

Fig. 13 shows the parts illustrated in Fig. 11 when the holding rod or member has been 70 completely released from the pail or the handle thereof.

The pail 1 is made of any suitable resilient metal, coated or uncoated, and it is adapted to contain a number of utensils 11 made of 75 similar material. The plates 2 are also made of any suitable resilient metal, coated or uncoated, and they are adapted to rest upon the upper utensils 11, so that they extend above the top of the pail 1. 80

The pail 1 is provided with lugs 5 and 6 which are adapted to be engaged by the ends 7 and 8 of a handle 4. The parts above described may be of any ordinary construction. 85

In order to releasably hold the utensils 11 and dishes 2 in place, a holding rod or member 3 made of resilient metal is provided. This resilient hook 3 has an arcuate end 9 and a U-shaped end 10. As clearly shown 90 in Fig. 1 for example, the ends 9 and 10 are adapted to embrace the ends 7 and 8 of the handle 4. As clearly shown in Figs. 1 and 6 for example, the member 3 extends above the lugs 5 and 6 and is located at one side of the handle 4, when the said handle is in the vertical position. The U-shaped end 10 of the member 3 has the lower branch or member thereof bent so that it serves as a latch as will be later more fully described. 95

The parts are so dimensioned that when they are in the position shown in Fig. 1, the resilient member 3 presses upon the dishes 2 so that the dishes 2 and the utensils 11 are firmly held in place. The end 7 of the handle 4 is so shaped, that when it is moved from the horizontal position, 100 105

shown in dotted lines in Fig. 6 to the full-line position shown in said Fig. 6, a downward pressure is exerted upon the end 10 of the member 3 so that the dishes 2 are locked in position. For convenience, this end 7 of the member 3 may be called the cam end, as it has a cam-like action upon the end 10 of the hook 3.

If it is desired to remove the dishes 2 and the utensils 11, the handle 4 is revolved into the horizontal position illustrated in Fig. 10 for example. A downward pressure is then exerted upon the end 10 of the member 3. This causes the member 3 to turn until end 9 assumes the position shown in Fig. 11. This turning movement causes the crotch of the end 10 to move inwardly with respect to the adjacent end 8 of the handle. A further downward pressure upon the end 10 as well as an inner movement thereof forces it into the position shown in Fig. 12, so that the member can be completely released as shown in Fig. 13 to enable the dishes 2 and utensils 11 to be readily removed.

It is therefore obvious that the member 3 can not be released and the dishes and utensils can not slip out of position when the handle is in the vertical position, because the member 3 is then forced downwardly and is locked against any inner movement. It is also obvious that when the handle 6 is moved to the horizontal position so as to release the pressure of its end 7 upon the member, that the dishes 2 may then be removed, although it is preferable to first completely release the end 10 of the member 3.

It is also obvious that the end 10 may be readily snapped into its locked position and that the angular contour of the outer member thereof produces an action similar to that of a latch.

I have described a preferred embodiment of my invention, but it is clear that numerous changes and omissions could be made without departing from its spirit.

It is obvious that the holding member 3 is connected to the pail adjacent the lugs thereof so that one pair of lugs are adapted to connect both the handle and the hook to the pail.

The handle 4 may be considered as part of the pail for the purposes of my invention,

since the holding member 3 is connected to 55 the pail after it is connected to the handle 4.

I claim:

1. In combination, a pail having perforated lugs, a handle connected to said lugs and having loop-like ends passing 60 through the perforations in said lugs, a holding member connected to said handle adjacent said lugs, the said holding member and said handle being of such contour that said handle contacts with said member when 65 it is moved to the upright position to force said holding member in a direction towards the bottom of said pail, each end of said member being free from and spaced from the perforations in said lugs. 70

2. In combination, a pail having perforated lugs, a handle for said pail having loop-like ends passing through said lugs, and a holding member directly contacting with the ends of said handle directly adjacent said lugs, each end of said holding member being free from and spaced from the perforations in said lugs. 75

3. In combination, a pail having perforated lugs, a handle having loop-like ends 80 passing through said lugs, a holding member having its ends directly contacting with said loop-like ends, each end of said holding member being free from and spaced from the perforations in said lugs, the contour of the ends of said holding member being such that it can be turned when it is in the said position, one end of the said holding member being of such contour that it can be released from the adjacent loop- 85 like end. 90

4. In combination, a pail having perforated lugs, a handle having loop-like ends passing through said lugs, a holding member having its ends directly contacting with 95 said loop-like ends, each end of said holding member being free from and spaced from the perforations in said lugs, one end of said holding member having an arcuate contour and the other end having an angular contour, so that said holding member can be turned and its end of angular contour can be released from the adjacent loop-like end. 100

In testimony whereof I hereunto affix my 105 signature.

ANDREW W. NELSON.
